GARRY J. DORMANDY, OF TROY, NEW YORK, ASSIGNOR TO LION COLLARS & SHIRTS, INC., OF TROY, NEW YORK, A CORPORATION OF NEW YORK.

COLLAR.

Application filed January 24, 1924. Serial No. 688,172.

As is well known, it is desirable in numerous collars that the longer of the two extensions at the ends of the neckband point higher than the band, or form a "lock-end", 5 so-called. That is to say, it is often desirable that the upper edge of the long extension form a reentrant angle with the upper edge of the body of the neckband. Such an upturned extension is adapted to interlock 10 underneath the fold at the opposite end of the collar and this helps to hold the points of the collar together and improves the fit about the neck. Usually this upturned extension is cut from the band material in 15 integral with the body portion of the neckband. My invention is directed toward providing such an upturned extension on collars in which the material of the band is such that it is unadapted to provide an integral 20 extension pointing higher than the body of the band, particularly when the upper edge of the neckband is formed by the selvage of the material from which the neckband is cut. The manner in which I do this will be understood 25 from the following description of particular applications of my invention, from which it will also be apparent that the invention is applicable to the shorter of the two end extensions if desired, or to both extensions. 30

In the accompanying drawing, Figure 1 is an elevation of the inside surface of a fold-over collar embodying my invention, the collar being opened out flat; Figures 2, 3 and 35 4 are similar elevations of single ends of other collars showing modifications; Figure 5 is a section of the collar of Fig. 1 on line 5-5; Figure 6 is an elevation of a single end of a further modification, and Figure 7 is 40 a section thereof on the line 7-7; Figure 8 illustrates how double selvaged material may be employed to reduce waste.

The collar construction shown in Figs. 1 to 5 does not differ materially from that 45 which has long been common, except that the upper edge of the band is selvaged and that the collars incorporate my invention. The band is composed of separate blanks or layers 1 and 2 of any suitable fabric which 50 is so cut from lengths of cloth that the natural selvage of the woven cloth forms the top edge of the body of the band blanks, i. e. from point A to point B. In the customary manner the blanks are infolded (for finish) 55 and sewn together at the lower edge 3 and

around the end of the shorter band extension 4. The top or fold-over 5 is inserted between the selvaged edges of the band fabrics, which are not infolded, and the whole sewn together by one or more lines of 60 stitching 6; the ends of the fold-over 5 are infolded and bound for finish in a well known manner. As is understood, the selvage at the top of the band blanks furnishes adequate finish in itself and hence renders 65 it unnecessary to infold the band material at this seam. By this means therefore the number of thicknesses of fabric at this seam is reduced to a minimum and a sharp-edge folding of the fold-over is made possible. 70 Since however the upper edges of the main or body portions of the band blanks (from A to B) are in fact the extreme edges of the fabrics from which the blanks are cut, it is 75 obviously impossible to so cut the goods that the upturned extension or lock-end 10, the upper edge of which forms a reentrant angle with the edge A-B of the band body, is integral with the body portion of the band blanks, for the edge of the goods is necessarily 80 substantially straight, or possibly is slightly curved in the opposite direction. The lock-end 10, it will be understood, is to extend under the top or fold-over 5 at the opposite end of the collar, so as to hold the 85 points of the collar together and support the front of the collar where the pressure of the neck or chin is likely to break it down. To provide a rising extension therefore, of which 10 is an example, I cut a separate 90 blank or blanks 11 and 12 therefor and attach these separate blanks to the end or ends of the body portion of the band along such seam or seams as 13, the outer one of which at least is disposed sufficiently to the rear to 95 be well covered by the fold-over 5 and thereby concealed from view when the collar is in use. As shown in Figure 1, for example, the upper edge of the upturned extension pieces 11 and 12 may be carried straight back to the 100 bottom of the band, the latter being cut off at a corresponding angle and the body and extension pieces being sewn together at 13 where they come in contact. Preferably at least so much of the edges of the extension pieces 11 and 12 are sewn to the band body pieces (from B to C in Figure 1) are selvaged edges and the body pieces are inserted 105 and sewn between these selvages, the latter being unfolded and laid flat against the out- 110

side of the body blanks of the band (Fig. 5), for this produces a finished seam containing a minimum number of thicknesses of fabric. In the construction of Fig. 1, this also brings 5 the selvages of the extension blanks 11 and 12 to the upper edge E of the completed extension 10 and requires no infolding or other finishing at this edge, although infolding or other finishing may be resorted to if desired. The remaining edges of the extension members 1 usually infold or they may 10 be otherwise finished. The joining of the two blanks or member 11 and 12 of the extension is completed by a line or lines of 15 stitching as indicated by the broken lines in the drawing. Figure 2 illustrates a construction in which the joining seam between the extension and the body of the band is farther to the rear of the collar; this may 20 be desirable to conceal the same in certain styles of collars. In this form, the extension blanks 11 and 12 may be selvaged from C to D as before, and infolded for finish from D to B and elsewhere. In certain cases 25 or with certain kinds of collars the seam or seams may be brought further to the front (Fig. 3). Figure 4 illustrates that the band pieces are not necessarily inserted between 30 selvaged edges of the extension blanks. In this instance the body and extension blanks are sewn together by entirely internal seams; this may be accomplished in various ways, for example by a process which involves hand turning of the band after these 35 pieces have been sewn together in a manner that will be understood by those skilled in the art. The broken lines 15 and 16 indicate the ends of the body blank and the extension blank respectively after the same 40 have been sewn together and then turned back and ironed flat against the inside of the band.

Since the band extensions may be made of any material, quite independent of the material used in the body of the band, my invention has the further advantage that it may be used to improve the appearance of the collar in certain instances. Thus in certain instances it is desirable that the band 45 and the fold-over be made of different materials. By making the long extension blanks or at least the outer blank 12 thereof (i. e. the one more remote from the neck of the wearer) of the same material as the fold-over, the collar when in use will seem 50 to be made of a single material throughout and a better appearance presented than is the case where that part of the band material which is exposed between ends of the fold-over above the tie is a quite different fabric 55 from that of the fold-over.

In the described constructions of Figs. 1 to 3, it will be observed that the number of thicknesses of fabric at the seam or seams 13, 60 equals at least the sum of the number of

thicknesses of fabric in the body of the band plus the number of thicknesses in the extension. In the present instance there are four thicknesses at this seam line, see Figure 5. Ordinarily this extra thickness at these 70 seams will not be objectionable but it is possible to reduce their number by offsetting these seams as illustrated in Figs. 6 and 7. In these figures the top edges of the extension blanks 11 and 12 are assumed to be selvaged as in Figure 1 (from C to B and at E). The inner extension blank 11 in Figure 6 (that one of the two blanks which is nearer the neck of the wearer) is set at a somewhat greater angle to the bottom edge of the band 75 than the outer extension blank. The seam 17 between the outer extension blank 12 and the outer blank 2 of the body of the band is somewhat higher and farther to the rear therefore than the seam 18 between the inner extension blank 11 and the inner body blank 1, so that the combined seams are somewhat wider than before, but in no part incorporate more than three thicknesses of cloth (Fig. 7). Furthermore, for illustrative 80 purposes the bottom edges of the blanks 1 and 2 of the band body of Figure 6 may be assumed to be selvaged edges like the upper edges of the band; that is to say, these body blanks 1 and 2 are cut from fabric that 85 is woven of exactly the same width as the body blanks. This practice leads to certain economies in the cutting of the fabric, for a portion of the woven material which otherwise is discarded as waste, can be readily 90 used effectively because of the two selvages which the strip material presents for use. Thus for example, Figure 8 illustrates a strip of band material of the same width as the body blanks 1 and 2 of the collar to be 95 made from it, and both edges of which are selvaged. By cutting this narrow strip of fabric along the broken line 21, the angular end (C to B) of one body blank is formed 100 ready for stitching to an extension member. By cutting off a piece of the remaining material along the broken line 22, an extension member or blank 11 or 12 is formed; reversing this extension blank, the bottom selvage of the strip at 23 becomes the top selvage of the extension blank, i. e. from C 105 to B and at E. Finally, cutting the remaining end of the strip along the line 24 forms the short-extension end of the next body blank, and the process is then repeated for 110 the entire length of the strip of fabric. The sole part of the material wasted therefore is that of the small pieces lying between the cutting lines 22 and 24. It is not necessary 115 that the extension blank 11 or 12 obtained in this way, be attached to the body blank 120 from which it is originally cut; it may be assembled in another collar or with a body blank cut from another strip of material. Therefore judicious assembly of extension 125

and body blanks obtained in this manner can bring about neckbands having a uniform appearance on each side although the strip fabric may be unlike on its two faces and the 5 body blank and extension blank cut in part from it must be relatively reversed before assembly.

It will be apparent that my invention may be used to provide an upturning interlocking extension wherever the nature of the collar fabric is such that a suitable extension can not be cut out of the fabric integral with the main or body portion of the neckband part of the collar, and that it is not limited 15 to the exact construction illustrated and described above except as appears in the following claims.

Claims—

1. A collar comprising a band member, 20 the upper edge of the main or body portion of which band member is a selvaged edge, and which band member has a separately-cut upturned extension attached to one end of its main or body portion and which extension reaches to a point above said upper 25 edge of the main or body portion of the band member.

2. The steps in the method of making a woven fabric collar which consists in cutting the band body portion from a woven fabric, separately cutting from a woven fabric a piece to extend from the end of said band body portion and form at its upper edge a re-entrant angle with the upper edge of said body portion, and sewing substantially the edge of said piece to substantially the end of said band body portion.

3. The steps in the method of making a fold-over collar from woven fabric which is 40 unadapted to provide an integral lock end, which consists in cutting the body portion of the band shorter than the fold-over at one end so that said end of the band body lies underneath the fold-over, separately cutting from woven fabric a lock-end piece to extend from said short end of the band body and form at its upper edge a re-entrant angle with the upper edge of said band body, and sewing substantially the edge of said 45 piece to substantially said end of said band body, so that the seam is concealed by the fold-over when the collar is in use and there 50

is produced on said end of the collar a lock-end adapted to extend under the fold-over at the opposite end of the collar and support the front where the pressure of the neck and chin tend to break down the front. 55

4. A collar comprising a neckband body member, the upper edge of which is selvage, a separate fold-over member attached to 60 said selvaged edge, and a separate extension member attached to an end of said band body member and reaching to a point above the upper edge of said body member.

5. A collar comprising a neckband body 65 member, the upper edge of which is selvage, a separate fold-over member attached to said selvaged edge, and a separate extension member, the upper edge of which is selvage and is sewn flat against one end of 70 said band body member, and said extension member reaching above the upper edge of said body member to interlock underneath the fold-over at the other end of the collar.

6. A collar comprising two neckband body 75 members the upper edges of which are selvages, a separate fold-over inserted between the same and sewn thereto, and an upturned interlocking extension at one end of the neckband consisting of two members the 80 upper edges of which are selvages and are laid flat against the outside of said neckband members and sewn thereto.

7. A collar comprising a neckband body portion, a fold-over, and a separately cut upwardly pointing extension at one end of the band consisting of two layers of fabric sewn to opposite sides of the neckband body, one of said layers reaching farther to the rear of the collar than the other and the two 90 layers being sewn to the neckband portion by individual lines of stitching. 85

8. A collar comprising a band member, which band member has a separately-cut extension attached to one end of its main or 95 body portion, one of the two longitudinal edges of the main or body portion of the band member being a selvage edge and the corresponding edge of the extension forming a re-entrant angle with said selvage edge. 100

In testimony whereof, I have signed this specification.

GARRY J. DORMANDY.
